UNITED STATES PATENT OFFICE.

ALLAN FRASER, OF BUFFALO, NEW YORK, ASSIGNOR TO PLAY-O-LITE COMPANY, OF BUFFALO, NEW YORK, A CORPORATION OF NEW YORK.

DESIGN FOR A PIANO-LAMP AND BRACKET.

53,395.

Specification for Design.

Patented June 3, 1919.

Application filed February 7, 1917. Serial No. 147,265. Term of patent 14 years.

To all whom it may concern:

Be it known that I, ALLAN FRASER, a citizen of the United States, residing at Buffalo, in the county of Erie and State of New York, have invented a new, original, and ornamental Design for a Piano-Lamp and Bracket, of which the following is a specification, reference being had to the accompanying drawing, forming part thereof.

Figure 1 is a perspective view from the top of a piano lamp and bracket showing my new design. Fig. 2 is a similar view from the underside of the piano lamp and bracket.

I claim:

The ornamental design for a piano lamp and bracket, as shown.

ALLAN FRASER.
